ELECTROMAGNETIC CONTACTOR.

1,310,269.

Specification of Letters Patent. Patented July 15, 1919.

Application filed June 28, 1916. Serial No. 106,383.

To all whom it may concern:

Be it known that I, REUBEN I. WRIGHT, a citizen of the United States, residing at Wickliffe-on-the-Lake, in the county of 5 Cuyahoga and State of Ohio, have invented new and useful Improvements in Electro-magnetic Contactors, of which the following is a specification.

This invention relates to electro-magnetic 10 contactors, and particularly to electro-magnetic contactors used in motor-control systems.

In some types of motor-control systems it 15 is the common practice to employ shunt-wound electro-magnetic contactors to successively cut out of the motor circuit the motor starting resistance sections, and to employ also electro-magnetic relays to govern the closure of the contactors. Various 20 arrangements have been devised for associating the relays and contactors together so that the closure of a contactor actuates its associated relay, and the subsequent operation of the relay controls the succeeding 25 contactor, and so on. Various attempts have been made also to associate the relay and the contactor in a structure so that the relay, when the contactor is open, will be held open mechanically by certain members of the contactor, such, for example, as the movable 30 contact arm, and also so that the relay will be held open electro-magnetically after the closure of the contactor, as, for example, by the motor current flowing through the contacts of the contactor, when this current is 35 above a predetermined value. But these structural arrangements have had the disadvantage that, during the time in which the contactor is closing, that is, after the 40 contactor has ceased to hold the relay open mechanically, and before the relay is held open magnetically, there is a period of time in which the relay is free to close and may close accidentally and result in an abnormal 45 operation of the system.

The contactors when employed in this manner are usually provided with arc-rupturing or blowout magnets, in order that the contactors may be opened in a practicable 50 manner to reinsert the sections of motor-starting resistance. It has heretofore been

the common practice to employ structurally independent relays and contactors, resulting in inexpensive and cumbersome apparatus.

One of the principal objects of this invention is to simplify the apparatus used in motor-control systems by providing a single electro-magnetic structure embodying the contactor proper, the blowout magnet, and the relay, and employing the winding of the relay as the energizing winding of the blowout magnet.

Another object of this invention is to provide an electro-magnetic contactor and relay in a single structure in which the relay contacts are held open mechanically by some part of the contactor when the contacts of the contactor are open, and held open electro-magnetically by motor current if above a predetermined value, after the contactor contacts have closed, the relay being prevented from moving toward the closed position during the whole time that the contacts of the contactor are moving from open to closed position.

Another object of this invention is to provide an electro-magnetic unit contactor which may be used as one of a train of like contactors in a motor-control system, and have main contacts for controlling a section of starting resistance and auxiliary contacts for governing the closure of a succeeding switch, the main and auxiliary contacts being associated together in the contactor structure in such manner that the auxiliary contacts will normally tend to close, but will be held open mechanically until the main contacts are closed, and will be held open electro-magnetically by motor current above a predetermined value.

Other objects will be apparent from the following description.

In the accompanying drawing, Figure 1 is a side elevation of my invention, partly in cross section, and with parts broken away; Fig. 2, a partial front elevation of the invention with the coil 43 omitted; and Fig. 3, a diagram of connections showing a motor-control system embodying my invention.

On the drawing, 10 represents the slate or other insulating base, upon which the parts

of the structure are mounted. The L-shaped magnet frame 11, having the core 12, which supports the winding 13 is mounted on the slate 10 by the stud 14 and the nut 15. The 5 stud 14 also serves as a connection point for an electric circuit to be described later.

Pivoted to the frame 11 at 16 is the movable magnetic contactor arm 17, having the pole face 18 magnetically co-acting with the 10 adjacent end of the core 12. The arm 17, normally occupies the open position shown, the stop 19 resting upon the frame 11. The ribbon connector 20, secured to the frame 11 at 21 and to the arm 17 at 22, forms an electrical shunt about the pivot 16. On the upper end of the arm 17 is the contact 23.

The iron bracket 24 is mounted on the slate by the bolt 25 and the nut 26, and has the web 27 and the flange 28. Pivoted to the 20 web 27 at 29 is the relatively stationary contactor-arm 30, on the upper end of which the contact 31 is secured. The spring 32 extends from the arm 30 to the flange 28, and normally holds the arm 30 against the stop 33 25 on the bottom of the flange 28.

The iron bracket 24 has an upwardly and forwardly extending wing 34, forming at 35 one of a pair of arc-rupturing or blowout magnetic poles. The other pole 36 of the 30 pair is provided by the downwardly and forwardly extending wing 37 of another bracket 38, mounted on the slate by the bolt 39 and the nut 40. The opposite faces of the blowout magnetic poles 35 and 36 lie in 35 parallel planes, the contacts 23 and 31 being between the poles. Each pole is provided with an arc-shield 41 which stands between the pole and the contacts.

Extending from the bracket 38 to the 40 bracket 24, with its axis vertical, is a non-magnetic spool 42, on which is wound a blowout coil 43, the terminals 44 and 45 of which are secured to the slates by the nuts 46 and 47. The terminal 44 also serves 45 as a connection point for an electric circuit to be described later. A ribbon connector 48 connects at one end with the terminal 45, and passing through a hole 49 in the slate, connects at the other end with the arm 30, being secured thereto by the screw 50.

The parts thus far described constitute the contactor proper of the unit structure. When the winding 13 is energized (the connections thereto not being shown), flux will 55 flow in the core 12, the frame 11, the arm 17, and the air gap between the pole face 18 and the pole 12, whereby the arm 17 will be drawn toward the core 12, bringing the contact 23 into engagement with the contact 31. If connections are made from an 60 electric circuit to the stud 14 and the terminal 44, current will flow in the following circuit: from the stud 14, through the frame 11, the ribbon connector 20, the arm 17, the

contacts 23 and 31, the arm 30, the ribbon 65 connector 48, the terminal 45, and the blowout coil 43 to the terminal 44. After the contacts 23 and 31 meet, the spring 32 will be compressed, and the relatively stationary arm 30 will be rotated counter clockwise into 70 the position shown in dotted lines at 51. The spring 32 then serves to hold the contacts 31 and 23 in firm engagement. The current flowing through the blowout coil 43 generates flux which flows say, upwardly through 75 the core of the spool 42 into the bracket 38, and thence to the wing 37 and the pole 36, and thence across the space between the shields 41 into the pole 35, the wing 34, and the bracket 24. When it is desired to break 80 the circuit which is closed at the contacts 23 and 31, the winding 13 is deenergized and the action of gravity on the arm 17, in connection with the action of the spring 32, causes the contacts 23 and 31 to be opened, 85 whereupon the arc which forms between them will be blown out by the magnetic flux just described, flowing between the poles 36 and 35.

The blowout coil 43 is made to serve as the 90 actuating coil of a relay, the parts of which will now be described. The stationary adjustable pole piece 52 is threaded into the bracket 38, and extends into the core of the spool 42, and the locknut 53 is provided to 95 secure it in any adjusted position. The plunger 54 is arranged to move vertically in the core of the spool 42. The lower end 55 of the plunger, which terminates in the pin 56, is separated from the main body 54 100 of the plunger by an insulator 57. The body portion of the insulator 57 is of greater diameter than the plunger 54 and the core of the spool 42, so that the insulator 57, besides insulating the two parts of the plunger from each other, provides a stop which, by engaging the lower end of the spool 42, serves to limit the upward movement of the plunger 54. To the upper end of the plunger 54 is secured a non-magnetic stem 58, 110 which passes upwardly through a central bore in the pole 52, and carries on its upper end the contact disk 59. The plunger 54, the stem 58, and the disk 59 are supported normally by the pin 56 resting on the arm 115 30. By adjustment of the pole 52 the air gap 63 between the lower end thereof and the upper end of the plunger 54, may be lengthened or shortened. When the blowout coil 43 is energized, the flux therefrom in 120 this air gap tends to pull the plunger 54 upwardly, the movement thereof being limited by the insulator 57. Mounted on the slate by the nuts 60 are the two studs 61, carrying the stationary relay contacts 62, adapted to 125 be engaged by the contact disk 59. The studs 61 also serve as connection points for control circuit connections to be described.

The operation of the relay will now be described. When the contactor contacts 23 and 31 are open, and the arm 30 is in its normal position, the pin 56 rests thereupon, 5 and the contact disk 59 is held upwardly out of engagement with the relay contacts 62. If, when the contact 23 is first moved into engagement with the contact 31, thus closing the main circuit, as has been de- 10 scribed, if the current flowing therethrough, and hence through the coil 43, is above a predetermined value, depending upon the adjustment of the adjustable pole 52, the plunger 54 will be held upwardly by the 15 flux from the blowout coil 43; and when the contacts 23 and 31 have moved to their full closed position, and the arm 30 occupies the position shown in dotted lines at 51, the plunger 54 will not fall until the 20 current through the contacts 31 and 23, and hence in the coil 43, falls to the predetermined value, the flux from the blowout coil then being insufficient to hold the plunger 54 upwardly, whereupon it will bring the 25 disk 59 down upon the relay contacts 62.

It is apparent that the plunger 54 and the pole 52 serve not only as parts of the relay, but as a part of the magnetic circuit of the blowout magnet. If the contacts 31 and 23 open before the plunger 54 has fallen, the air gap 63 will be of minimum length, and the reluctance of the magnetic circuit of the magnetic blowout will be at a minimum, and the arc will be blown out effectively. On 35 the other hand, if the plunger 54 has fallen before the contacts 31 and 23 open, it will be raised again by the initial opening movement of the arm 30 acting on the pin 56 before the contacts 31 and 23 have actually 40 separated sufficiently to draw an arc, and hence in this case also the air gap 63 will be at a minimum and will not introduce reluctance in the magnetic circuit of the blowout magnet.

One of the uses to which my invention 45 may be put in connection with motor control systems, will now be described.

Referring to Fig. 3, A represents the armature and F the shunt field of the motor, 50 R¹ and R² the sections of the starting resistance, H a master controller, S¹ and S² diagrammatic representations of the unit structure shown in Fig. 1, and S³ a shunt-wound magnetic contactor of any well 55 known and suitable form. Each of the contactors S¹, S², and S³ has the main contacts 31 and 23, the actuating winding 13, the blowout coil 43, the contactor arms 17 and 30; and the contactors S¹ and S² have also 60 the relay plunger 54, the contact disk 59, and the relay contacts 62.

Upon moving the master controller H to the full-on position, so that the arm h is in engagement with the three contacts h¹, h²,

h³, the winding 13 of the contactor S¹ is 65 energized, the control current flowing from the positive main 64, through the arm h, the contact h¹, the winding 13, and the wire 65 to the negative main 67. The contacts 31 and 23 are closed by the coil 13, and motor 70 current flows from the positive main 64 through the arm 17 of the contactor S¹, the contacts 23 and 31, the connector 48, the blowout coil 43, the resistance sections R¹ and R², and the motor armature A to the 75 negative main 67. The motor starts, and the current being above the predetermined value for which the relay of the contactor S¹ is adjusted, the plunger 54 of this relay is held upwardly and the contacts 62 of the 80 relay remain open. After the starting current falls to the predetermined value, the plunger 54 falls, and the disk 59 closes the contacts of the relay, thereby admitting current to the winding 13 of the contactor S², 85 current thereto flowing from the main 64, through the arm h, the master contact h², the contacts 62 of the relay on the contactor S¹, the winding 13 of the contactor S², and the wire 65 to the main 67. The contacts 31 90 and 23 of the contactor S² now close, short-circuiting the resistance section R¹ and holding the relay contacts of the contactor S² open. Subsequently, when the motor current falls to the predetermined value for 95 which the relay of the contactor S² is adjusted, the relay contacts of the contactor S² close as was the case with the contactor S¹, and admit current to the winding 13 of the contactor S³. The contacts 31 and 23 of the 100 contactor S³ close, shortcircuiting the resistance section R², whereupon the motor is brought up to full speed.

While the control system as described will operate automatically to bring the motor up 105 to full speed, when the master handle h is thrown to the full-on position, it is apparent that each contactor S¹, S², or S³, can be prevented from closing by holding the master arm h out of engagement with the corresponding master contacts h¹, h², or h³, respectively. Likewise, after the closure of any contactor S¹, S², or S³, it may be caused to open and reinsert the starting resistance, or open the motor circuit, as the case may 115 be, by moving the master arm h out of engagement with the corresponding master contact, and when one of the contactors S¹, S², or S³ is thus opened, the arc caused thereby on the contacts 31 and 23 will be 120 blown out by the flux generated by the coil 43, as has been described.

My invention is not limited to the exact form of the various parts of the unit structure or device in Figs. 1 and 2, nor to the 125 particular diagram of connections illustrated in Fig. 3, by which the device may be applied to motor-control systems, since the

invention may be embodied in various forms and applied to other uses, without departing from the spirit of my invention or sacrificing its advantages.

5 I claim—

1. In a switching device, a main contactor, an arc-rupturing magnet therefor, and an electromagnetic contactor normally in open position, the winding of the electromagnetic contactor being the energizing winding of the arc-rupturing magnet.
2. In an electromagnetic switch structure, a main contactor, an arc-rupturing magnet therefor comprising pole pieces and a magnetic circuit, and an electromagnetic contactor with normally open contacts, the winding of the electromagnetic contactor being the energizing winding of the arc-rupturing magnet and the movable member of the electromagnetic contactor constituting a part of the magnetic circuit of the arc-rupturing magnet.
3. In an electromagnetic structure, a main contactor, an arc-rupturing magnet therefor containing a winding and stationary pole pieces, and an electromagnetic contactor, the winding of the electromagnetic contactor being the energizing winding of the arc-rupturing magnet.
4. In an electromagnetic switch structure, a main contactor, an arc-rupturing magnet therefor containing a winding, a magnetic circuit and stationary magnetic pole pieces, an electromagnetic contactor, and a movable magnetic operating core member therefor, the winding and the core member of the electromagnetic contactor being respectively the energizing winding for the arc-rupturing magnet and a part of the magnetic circuit thereof.
5. In a switch structure, a normally open main contactor, an arc-rupturing magnet therefor containing a winding and a magnetic circuit, the magnetic circuit comprising stationary magnetic pole pieces and an intermediate magnetic member, a normally open electromagnetic contactor, and a movable operating magnetic member therefor, the winding and the operating member of the electromagnetic contactor being respectively the energizing winding and the intermediate magnetic member of the arc-rupturing magnet.
6. In a switch structure, a main contactor containing a first main contact, a second main contact and a carrying member therefor, means for causing the first main contact to move into engagement with the second main contact and to move the second main contact and its carrying member, and an auxiliary contactor having a movable contact normally biased to move but mechanically restrained from movement by the carrying member.
7. In a switch structure, a main contactor containing a first main contact, a second main contact and a carrying member therefor, means for causing the first main contact to move into engagement with the second main contact and to move the second main contact and its carrying member, and an auxiliary contactor having a movable contact normally biased to move but mechanically restrained from movement by one carrying member until after the engagement of the main contacts.
8. In a switch structure, a main contactor containing a first main contact, a second main contact and a carrying member therefor, means for causing the first main contact to move into engagement with the second main contact and to move the second main contact and its carrying member, and an auxiliary contactor having a movable contact normally biased to move but mechanically restrained from movement by the carrying member until after the movement of the carrying member by the engagement of the main contacts.
9. In a switch structure, a main contactor containing a first main contact, a second main contact and a carrying member therefor, means for causing the first main contact to move into engagement with the second main contact and to move the second main contact and its carrying member, an auxiliary contact normally biased to move but mechanically restrained from movement by the carrying member, and a winding controlling the auxiliary contact, energized through the main contacts and adapted to magnetically restrain the auxiliary contact from movement after the engagement of the main contacts.
10. In a switch structure, a main contactor containing a first main contact, a second main contact and a carrying member therefor, means for causing the first main contact to move into engagement with the second main contact and to move the second main contact and its carrying member, an auxiliary contact normally biased to move but mechanically restrained from movement by the carrying member, and a winding controlling the auxiliary contact, energized through the main contacts and adapted to magnetically restrain the auxiliary contact from movement after the movement of the carrying member by engagement of the main contacts.
11. In a switch structure, a main contactor containing a first main contact, and a second main contact and a carrying member therefor, means for causing the first main contact to move into engagement with the second main contact and to move the second main contact and its carrying member, an auxiliary contact normally biased to move but

mechanically restrained from movement by the carrying member, and a winding controlling the auxiliary contact, energized through the main contacts and adapted to 5 magnetically restrain the auxiliary contact from movement after the engagement of the

Copies of this patent may be obtained for five cents each, by addressing the "Commissioner of Patents, Washington, D. C."

main contacts when the current in the winding is above a predetermined value only.

Signed at Cleveland, Ohio, this 24th day of June, 1916.
